[57] CLAIM

The ornamental design for an endoscopic bib, as shown and described.

DESCRIPTION

FIG. 1 is a perspective view of an endoscopic bib showing my new design;

FIG. 2 is a top plan view thereof;

FIG. 3 is a front view thereof;

FIG. 4 is a back view thereof;

FIG. 5 is a right side elevational view thereof;

FIG. 6 is a bottom view thereof; and,

FIG. 7 is a perspective view thereof shown in use, the broken lines showing a patient and table being for illustrative purposes only and forming no part of the claimed design.

Fig. 1.

Fig. 2.

Fig. 3.

Fig. 4.

Fig. 5.

Fig. 6.

FIG. 7.
